Specification for Design.

Patented Apr. 5, 1921.

Application filed March 15, 1919. Serial No. 282,992. Term of patent 14 years.

To all whom it may concern:

Be it known that I, WARD HARRISON, a citizen of the United States, residing at Cleveland, in the county of Cuyahoga, State of Ohio, have invented a new, original, and ornamental Design for Lighting-Globes, of which the following is a specification, reference being had to the accompanying drawing, forming a part thereof.

The figure is an elevational view of a globe comprising my new invention.

I claim:

The ornamental design for a lighting globe substantially as shown.

In witness whereof, I have hereunto set my hand this eleventh day of March, 1919.

WARD HARRISON.
